DISPENSING NOZZLE GUARD

Eugene G. Sutcliffe, 3706 Greenwood Blvd.,
St. Louis 17, Mo.

Filed Sept. 8, 1960, Ser. No. 62,066

Term of patent 14 years

(Cl. D91—1)

FIG. 2.

FIGURE 1 is a side elevational view of a dispensing nozzle guard, showing my new design, with the broken line portions shown for illustrative purposes only;

FIGURE 2 is an end view of the guard shown in FIGURE 1; and

FIGURE 3 is a top plan view thereof.

The undisclosed side of the nozzle guard is substantially the same in appearance as the side shown.

I claim:

The ornamental design for a dispensing nozzle guard, substantially as shown and described.
